UNITED STATES PATENT OFFICE.

FREDERICK H. RACKLE, OF HARTFORD, CONNECTICUT, ASSIGNOR TO THE SMITH-WORTHINGTON COMPANY, OF HARTFORD, CONNECTICUT, A CORPORATION OF CONNECTICUT.

JOCKEY-PLATE.

1,136,267.

Specification of Letters Patent.

Patented Apr. 20, 1915.

Application filed April 11, 1911. Serial No. 620,505.

To all whom it may concern:

Be it known that I, FREDERICK H. RACKLE, a citizen of the United States, residing at Hartford, in the county of Hartford and 5 State of Connecticut, have invented a new and useful Improvement in Jockey-Plates, of which the following is a specification.

It has been customary to provide the saddle of a heavy single harness, such for 10 instance as is used for express and the like delivery teams, with jockey plates. One of these is attached to each side of the saddle skirt and the back band, which is run inside of the saddle at the top and passes through 15 these jockey plates to the outside. This invention relates to the construction of such plates.

Jockey plates have been made in a single piece and of two pieces, but universally have 20 been attached to the saddle by means of screws that are inserted through the plate and saddle skirt from the front. It has been common, when the plates are formed of two pieces, to use two screws with slotted or 25 with enlarged angular heads for holding the parts together and securing the whole to the saddle. It has also been common to fasten such plates, when made of a single piece, with slotted screws set in from the 30 front through the lower part or web of the plate. Plates formed in this manner are more or less expensive to make, and they collect dust and dirt and are inconvenient to clean. Furthermore, the fastening screws 35 are quite likely to work loose and drop off or to chafe and wear the back strap.

The object of this invention is to provide a very simple and cheap single piece jockey plate which can be securely attached by 40 simple fastenings, that are inserted from the back when the saddle is being made, in such manner that they cannot work loose and drop out or chafe the back band, and whereby the front of the plate is left perfectly 45 smooth so that it will not catch dust and dirt, and can be easily cleaned and polished.

Figure 1 of the accompanying drawings shows a front view of a jockey plate which

embodies the invention. Fig. 2 shows a vertical section on the plane indicated by the 50 dotted line 2—2 on Fig. 1. Fig. 3 shows a back view of the plate, and Fig. 4 shows a horizontal section on the plane indicated by the dotted line 4—4 on Fig. 3.

These plates are usually formed of brass 55 or nickel, and they may have any desired peripheral outline but preferably are oval or circular. The plate which is illustrated has a yoke section 1 which on the front is rounded over on the outside edge 2, and 60 also rounded over on the inside edge 3. Joining the lower ends of the yoke section is a web 4. This web slopes outwardly from its inner to its outer edge. The inner edge 5 is back of the plane of the back face of the 65 yoke section of the plate, while the outer edge 6 is in the plane of the back face of the yoke. This provides a slanting chafing surface for the back band which passes downwardly from beneath the saddle 70 through the opening 7 and over the web of the jockey plate. Formed integral with, and projecting inwardly from each side of the back face of the plate is a hub 8. These hubs are provided with threaded sockets 9. 75 In order to fasten this plate in position, it is placed over the back-hand opening in the saddle skirt with the hubs extending through perforations in the skirt. Ordinary screws are then inserted from the back and 80 screwed into the threaded sockets in the hubs before the saddle panel is stitched to the skirt. This construction results in a jockey plate which is very simple to make and very easy and cheap to attach by ordinary fastening means. There are no obstructions or perforations on the front, as the fastening means are concealed, thus the outer surface does not readily accumulate 85 dirt and dust, and can be very quickly 90 polished.

The invention claimed is:

As an article of manufacture a jockey plate having a U-shaped body with an unbroken and imperforate convex front surface and circular outline, with an upwardly 95

and backwardly extending integral flat web between the ends of said body, the lower edge of said web being circular and the upper edge straight, and bosses that project from the back face of the body on diametrically opposite sides of the opening therethrough, said bosses being integral with the

body and having rearwardly opening threaded sockets.

FREDERICK H. RACKLE.
